UNITED STATES PATENT OFFICE

2,025,646

APPARATUS FOR THE MANUFACTURE OF CIGAR-FILLERS.

Theodorus Collé, Culemborg, Netherlands, assignor to Adriaan Marie Johan Dresselhuijs, The Hague, Netherlands

Application September 5, 1934, Serial No. 742,779
In the Netherlands July 12, 1933

4 Claims. (Cl. 131—39)

The invention relates to an improved apparatus for the manufacture of cigar-filters.

Up till now it was rather difficult to make cigar-filters and more particularly those of a larger size, having a uniform compactness of tobacco, which is of primary importance particularly with respect to the regular burning of the cigar.

The apparatus according to the invention entirely realizes this object in that a reciprocating rake-shaped pressure mechanism with fingers controlled by springs is provided, by which means the tobacco is pressed under a certain pressure from a hopper into a metal tobacco-mold. The tobacco may then be cut off, after which the contents of the mold may be pressed by means of a stamping-device into a wrapping-cloth to be wrapped in the usual manner with a bunch-wrapper or binder into a filler. The tension of the springs of the fingers associated therewith can be adjusted, and moreover the movement of the pressure mechanism is such that the fingers are ineffective at the upstroke, while at the down-stroke they press the tobacco from the interior of the hopper into the mold.

In this way a considerable advantage is obtained as the tobacco is perfectly equally divided into the mold, while the compactness of the filler can be increased or reduced by changing the tension of the springs.

In order to be able to remove the tobacco from the mold this is moved first horizontally from below the hopper to the stamping-device and next vertically to reach the wrapping-cloth, after which the tobacco is removed from the mold into the wrapping-cloth by means of a stamp.

According to the invention the stamping-device comprises a bow which is guided by two vertical rails so as to be capable of motion to and from the wrapping-cloth, a stamp made of wood or similar material, and a spring between the bow and the stamp which permits the stamp to continue its vertical movement to a certain extent after the bow has reached its lowest position.

According to the invention both the periodical movement of the supplying-mechanism and of the stamping-device may be effected efficaciously from a revolving toothed segment.

The invention will be more clearly understood from the description of a suitable embodiment of it with reference to the accompanying drawings, wherein:

Fig. 1 shows a schematic side-view of the apparatus,

Fig. 2 is an enlarged plan view,

Fig. 3 shows an enlarged portion of Fig. 1 with certain parts omitted, and shows a side-view of the rake-shaped pressure-mechanism,

Fig. 4 is an enlarged section along the line IV—IV of Fig. 2.

Fig. 5 is an enlarged side-view of the stamping-device and the wrapping-cloth, and

Fig. 6 is a perspective view of the pressure mechanism.

In the drawings 1 indicates the frame of the machine on which the shaft 3 with its fly-wheel, 2, which is driven by any suitable means, is mounted. This shaft 3 drives a shaft 8 provided with a toothed segment 7 by means of a chain 4 and sprockets 5 and 6. By rotating the toothed segment 7 a revolving motion periodically is communicated to the pinion 10 fixed on the shaft 9, which motion is transmitted by the shaft 9 on which are secured both the driving wheels 11, 12 and a crank 13. The crank-pin 14 and the crank 13 are connected with a rod 17 provided with fork-shaped ends 15 and 16 of which the fork-shaped end 15 is hinged with a rod 18 which in its turn is linked by a hinged connection to two plates fixed to the table 19. The other fork-shaped end 16 of rod 17 is provided with a shaft 20 having a number of say six fingers 21 mounted pivotally thereon. The slightly pointed extremity of each finger extends through a slit 22 in the lower part of the hopper 23 containing the tobacco, whereas the other end is connected to a spring 24. Moreover said springs 24 are connected to a rod 25 which, by means of the nuts 27 screwed on the bolts 26, may be adjusted higher or lower either to increase or reduce the tension of the springs. A vertically placed plate 28 embraces the bolts 26 and is held tightly in place by nuts 29.

On each side of the hopper 23 the periodically revolving supplying-bands 31 and 32 are placed which are driven by means of the belts 35 and 36 from the shaft 9 by the pulleys 11, 33 and 34. The shaft 9 is driven as elsewhere stated, by the shaft 10 to which a periodic movement is imparted by the segment 7. By means of the pulleys 12 and 37 and the belt 38 a roller 40 is periodically being rotated round the shaft 39 for guiding the tobacco from the bottom of the hopper into the tobacco-mold 47. A knife 41 (Figs. 1 and 2) which is fixed to a rod 43 pivotally mounted at 42, is held in its utmost left position (i. e. not active) by a spring 44 and at definite periods driven to the right-hand side by means of a rod 45. Said rod 45 which pivots at 46 is driven by any

suitable means, e. g. by means of a cam on the shaft 3.

In order to supply a definite amount of tobacco, the apparatus according to the invention has an open metal tobacco-mold 47 of which the bottom is formed by the table 19 over which the mold is horizontally movable. This horizontal movement is periodical and is effected by means of a rod 48 pivotally mounted at 50 and having a fork-shaped end 49 and a cam on the shaft 3; the rod 48 is continually being pressed against cam 3 by means of a spring 48a. The fork-shaped end 49 is provided with a projection 51 which fits into a recess 52 of the tobacco-mold 47. The part to be filled with tobacco may have the shape as represented by the dotted rectangle in Fig. 2. It may of course also be shaped otherwise according to the size and shape of the cigar as desired.

In its extreme right-handed position the mold 47 is situated below the stamping-device of which the principal features are a bow 53, that can take up the mold 47 and a stamp 54 made of wood or similar material that is fixed to a plate 55. To this plate 55, above the stamp 54 a shaft 56 is mounted, having at its top a guide 57 round which shaft 56 between the stop 58 engaging the bow 53 and the plate 55 a spring 59 is provided. The bow 53, which can move vertically along rails 60 of the vertically projecting posts 61, is provided at the lower end with two supports 62 for the mold 47. The vertical movement of the stamping-device is effected by a roller 63 on the toothed segment 7 (Fig. 1) which cooperates with a tongue 64 on the lever 66 pivoted at 65, which in its turn communicates the movement to the link 67 and lever 68. Lever 68 turning at 69 is provided at its end with a roller 70, that rolls along guide 57 on spindle 56. In order to place bow 53 with its mold supports 62 at the right height, an adjustable stop 71 is placed below lever 66; lever 66 is constantly pulled down by spring 72.

For wrapping the cigar-filler, a container 73 is placed under the stamping device to which a board 74 is fixed; just over it a roller 75 is movable, which is fixed to two rods 77 guided in tubes 76 which in their turn can be moved periodically by a system of rods 80 and 80' pivoted at 78 and 79 and connected by link 80' and for instance a cam on the shaft 3. Spring 81 presses the rod 80 continually to shaft 3. Over the container 73, roller 75 and the board 74, wrapping cloth 82 is placed which can be rolled up more or less by the roller 84 revolving on spindle 83.

The apparatus according to the invention functions as follows:

In the position of the toothed segment 7 shown in Fig. 2 the mold 47 is situated under the hopper 23. If the toothed segment 7 is set in motion in the direction of the arrow (Fig. 1) shaft 9 makes a number of revolutions—e. g. three—while the supply belts 31, 32, the roller 40 and crank 13 are moved too. The rake-shaped pressure-mechanism 17 thereby is alternatively lifted and dropped three times so that the fingers 21 at the down-stroke press the tobacco from the hopper 23 under a certain pressure into the tobacco mold 47. However during the up-stroke they remain outside of the slits and therefore do not affect the movement of the tobacco.

As soon as the toothed segment 7 has passed the pinion 10, the fingers 21 stay at their top-height and the tobacco is then cut off by the knife 41. Next the tobacco-mold 47 filled with tobacco is pushed along the table 19 by means of rod 48 to the stamping-device. The knife

however remains in the position as given in Fig. 1 in order to prevent the tobacco from dropping from the hopper while mold 47 is removed.

At the moment that mold 47 has arrived under the stamping-device, roller 63 of the toothed segment 7 is in front of the tongue 64 of lever 66. The movement being continued, cam 64 is pressed down and with it stamp 54 and bow 53 together with the tobacco-mold 47 on it. After the support 62 has arrived at the bottom of the container 73 the downward motion continues for a short time so that against the pressure of spring 59 the stamp 54 is pressed through the mold 47 filled with tobacco and into the wrapping-cloth.

Spring 72 presses lever 66 again on stop 71 so that the stamp retakes its position over the mold and at the level of table 19. While the mold is moved back to the hopper 23, roller 75 under the wrapping cloth 82 is moved to the right so that in the normal way the filler is wrapped in a binder.

When the mold is under the trough again, the knife 41 is pulled back by the spring 44 and its rake-shaped pressing-mechanism can again perform its up- and downward movement.

What I claim and desire to secure by Letters Patent is:

1. In an apparatus for the manufacture of cigar-filters having a hopper for the material, a horizontally slideable mold under said hopper, a horizontally slideable knife between said mold and said hopper, and means for removing the contents of said mold into a wrapper, the combination of a rake-shaped pressure mechanism having fingers and means for mechanically pushing said fingers into said hopper on their downward stroke and withdrawing said fingers from said hopper on their upward stroke, said fingers being pivotally supported by said pressure mechanism, and spring means connecting said fingers and said mechanism for forcing the active extremities of said fingers downwardly.

2. In an apparatus for the manufacture of cigar-filters having a hopper for the material, a horizontally slideable mold under said hopper, a horizontally slideable knife between said hopper and said mold and means for removing the contents of said mold into a wrapper, the combination of a rake-shaped pressure mechanism having fingers, said pressure mechanism being pivotally connected to a link pivotally mounted on the frame of the apparatus and a rotatable crank connected to said pressure mechanism adapted to push said fingers into said hopper while simultaneously giving them a downward motion and to withdraw said fingers from said hopper while simultaneously giving them an upward motion.

3. In an apparatus for the manufacture of cigar-filters having a hopper for the material, a horizontally slideable mold under said hopper, a horizontally slideable knife between said hopper and said mold and means for removing the contents of said mold into a wrapper, the combination of a rake-shaped pressure mechanism having fingers, said pressure mechanism being pivotally connected to a link pivotally mounted on the frame of the apparatus and a rotatable crank connected to said pressure mechanism adapted to push said fingers into said hopper while simultaneously giving them a downward motion and to withdraw said fingers from said hopper simultaneously giving them an upward motion, said fingers being pivotally supported by said pressure mechanism and connected to said mechanism by 75

means of springs forcing the active extremities of said fingers downwardly.

4. In an apparatus for the manufacture of cigar-filters having a hopper for the material, a horizontally slideable mold under said hopper, a horizontally slideable knife between said hopper and said mold and means for removing the contents of said mold into a wrapper, the combination of means for removing material from said supply hopper comprising a forked link pivotally supported on the frame of the apparatus, a rotatable crank connected to said link, a shaft connecting the branches of said forked link and

fingers pivoted intermediate their length upon said shaft, bolts supported from said link and on each side thereof, a rod extending from one of said bolts to the other above said link and supported thereon, means for adjusting said rod on said bolts, and springs extending from said rod to each of said fingers on that side of the pivot furthest from the hopper whereby said fingers enter said hopper and travel downwardly under a controlled pressure, and return to their position exterior to the hopper. 5 10

THEODORUS COLLÉ.
